EVAPORATOR STRUCTURE

Franklin G. Slagel, Buffalo, N. Y., assignor to
Fedders Manufacturing Company, Inc., Buffalo,
N. Y., a corporation of New York

Application December 31, 1931, Serial No. 584,212

2 Claims. (Cl. 62—126)

This invention relates to mechanical refrigerating systems and more particularly to evaporator structures.

In order to speed up the transfer of heat from food and liquids stored in evaporators, it has been proposed to form and connect shelves with the evaporators so that refrigerant circulating in the evaporator flows through the shelves.

An object of this invention is to provide a new and novel form of refrigerated evaporator shelf.

Another object of the invention is to provide a shelf for evaporators which has conduit or duct means associated intimately therewith and connected with the evaporator refrigerant circuit so that refrigerant flows therethrough.

A further object of the invention is to provide a refrigerated form of shelf for evaporators which can be cheaply manufactured and installed.

Other objects of the invention will appear from the following description taken in connection with the drawing, which forms a part of the specification, and in which:

Fig. 1 is a perspective view of an evaporator having a refrigerated shelf incorporating my invention associated therewith.

Fig. 2 is a plan view of the shelf removed from the evaporator.

Fig. 3 is a side elevation of the shelf.

Fig. 4 is a sectional view of the shelf taken on line 4—4 of Fig. 2.

Fig. 5 is a sectional view of the shelf taken on line 5—5 of Fig. 2.

Fig. 6 is a sectional view of the shelf taken on line 6—6 of Fig. 2.

Referring now to the drawing by characters of reference, 10 indicates generally a flooded type of evaporator adapted to be connected in circuit with a conventional form of compressor and condenser. The illustrated evaporator consists of a header 11 and a storage chamber housing formed of two sheets of metal 12 and 13. The outer sheet is formed with parallel pressed out bosses 14 which with the associated sheet form a plurality of conduits or duct means encircling the storage chamber and communicating with the interior of the header. The ends of the sheets are welded together as indicated at 15 and the adjacent edges of the sheets are welded together, as indicated at 16. The sheets are also welded together intermediate the bosses, and the upper ends of the bosses are secured to the header. The header is of conventional design and can be connected in the refrigerating system in the usual manner by means of an inlet connection 17 and an outlet connection 18.

Within the chamber I propose to fix a novel form of refrigerated shelf with which refrigerant in the evaporator circulates in intimate contact.

The shelf in this instance is formed of two sheets of metal 19 and 20. The top sheet is longer than the bottom sheet, the ends thereof being bent around to enclose the same, as indicated at 21. The intermediate portion of the top sheet is wider than the under sheet, and the overlying side portions thereof are turned down thereby serving to strengthen the unit and to cover the edges. The top sheet is also formed with rails 23 which are pressed upwardly in parallel relation to serve as bearing surfaces for receptacles inserted into the storage chamber of the housing.

Extending across each end portion of the shelf is a manifold or header 24, such manifolds being formed partly by the upper and lower sheets of metal. Connecting the manifolds are ducts 25 which extend in parallel relation longitudinally of the shelf. To form these ducts the lower sheet is formed with depressed spaced ribs 26 terminating transversely extending ribs 27 which form the lower part of the manifolds. The upper sheet is substantially flat, except for the rails, the side flanges and semi-circular extensions 28 which form a continuation of the manifolds. Such extensions are formed semi-circular and mate with extended portions 29 of the lower sheet, there being flange portions 40 suitably secured together. The extreme ends of the semi-circular extensions terminate in vertically extending flanges 30. Between the rails and beyond the manifolds, the sheets are welded together as indicated at 31, thus sealing the refrigerant duct means formed by the manifolds and the ducts connecting the same.

The front and the rear evaporator conduit loops 14 are formed openings around which the flanges 30 are arranged and secured to the chamber wall by welding or some other similar method. The evaporator is preferably of the flooded type and the conduits 14 are thus filled with refrigerant at all times. As the manifolds are in open communication with the end conduits, they and the connecting ducts 25 therebetween will also be filled with refrigerant. Refrigerant flows into the header through the connection 17 and refrigerant gas escapes through the connection 18, suitable automatic control mechanism of a conventional type being utilized within the header to maintain a constant quantity of refrigerant in the header.

It will be seen that the shelf headers com-

110

5 municate with the refrigerant in the duct means encircling the evaporator chamber and that refrigerant in the shelf headers can flow from one to the other through the parallel duct means in the shelf. The refrigerant will circulate freely through the shelf and thus a low shelf temperature is maintained so that quick freezing of liquids supported thereon will take place. As the shelf consists of only two sheets of metal, it

10 can be cheaply manufactured.

15 Although the invention has been described in connection with certain specific embodiments the principles involved are susceptible of numerous other applications which will readily occur to persons skilled in the art, and the invention is therefore to be limited only as indicated by the scope of the appended claims.

What I claim is:

20 1. A shelf for refrigeration evaporators, comprising a pair of superimposed sheets of metal, the lower of said sheets being formed with a transverse depending rib adjacent its transverse mar-

gins, said ribs forming spaced header portions between said sheets open at opposite ends, said lower sheet being also formed with a plurality of longitudinally extending depending portions forming ducts between said sheets for connecting said headers, means securing said sheets, and flange means at opposite ends of said headers, each adapted for connection with an evaporator.

2. A shelf for refrigeration evaporators, comprising a pair of superimposed sheets of metal, headers traversing the interior of the shelf adjacent opposite transverse margins, and longitudinal ducts connecting said headers, said headers and ducts being formed out of the lower of the sheets, and the upper sheet having a substantially planar surface formed with longitudinally extending rails for supporting an ice tray in spaced relation to said surface, said rails being substantially coextensive with the ducts in the lower sheet.
